UNITED STATES PATENT OFFICE.

THOMAS C. SPELLING, OF NEW YORK, N. Y.

SHIFTABLE CLOSURE.

1,249,541.

Specification of Letters Patent. Patented Dec. 11, 1917.

Application filed January 30, 1917. Serial No. 145,404.

To all whom it may concern:

Be it known that THOMAS CARL SPELLING, a citizen of the United States, residing at New York, in the county of New York and 5 State of New York, has invented certain new and useful Improvements in Shiftable Closures, of which the following is a specification.

This invention relates to stoppers and caps 10 for bottles, demijohns, jars cartons, and other containers of liquid and other flowing or fine grained substances, such, for instance, as granulated sugar, gunpowder, sulfates, phosphates, etc. Its purpose is the provision 15 of a very simple vent for opening and closing such containers, without the necessity of complete removal of the sealing member from the neck of the bottle, the parts being durable and comparatively cheap in the matter of manufacture and assemblage.

The forms and functions of the various parts, as well as their relation to and co-action with each other will fully appear 20 from the following specific description and 25 illustration.

In the drawings, Figure 1 is a perspective view of the assembled device, the stopper and its adjuncts being shown in elevation, preparatory to pouring liquid from an ordinary bottle; Fig. 2 is a view, with the arms in position, after being pulled down ready 30 to be moved into lock; Fig. 3 is a sectional view on the lines 3—3, of Fig. 2; and Fig. 35 4 is a perspective view of the stopper, showing the groove or cut-away, therein, and the sieve. Fig. 5 of the drawing is a perspective view of applicant's structure in assembled and locked position, showing the side-mouth and its protector in assembled relation.

40 Referring more in detail to the drawings, wherein like reference characters designate similar parts in the several views, A is a bottle neck having thereon the shoulder B, above which is located the mouth C, the gap 45 in the rim hereinafter designated as a side-mouth D, and the spout E. The cap has the curved gripping extensions F, the apex G, the shoulders H, the transverse side-opening I, the shield J, carrying the member 50 hereinafter termed the protector K, the vertical slots L, the horizontal slots M, and the gap N. The puller here employed is a modification of that already covered by Letters Patent issued to me, and numbered 1,216,177,

dated February 13, 1917. It has the wire 55 engagement of the arms C, the arms P, resting on the core at Q, and the anchoring portion or core R. The construction, emplacing and securing of this member in the stopper are fully described in said Letters 60 Patent, to which reference is here made, without insertion in detail. The modification consists in extending the upper end of the core above the stopper, as shown in the drawing. 65

I do not, however, limit myself in this invention to that or any other pull means, because stoppers made of glass and other materials may be better adapted in some instances than cork or other yieldable substances and other means of engagement may thus become more serviceable. 70

The stopper is grooved or cut away at S, so that the contents of the container may have ingress and egress without the necessity 75 of removing the stopper entirely from the neck of the bottle. In the cut-away space may be attached the sieve T. The diminution of the stopper resulting from this cutting away of a portion of it to form the 80 groove also facilitates its reinsertion below the mouth after the stopper has been elevated, in use, to empty some of the contents of the bottle, though of course, the primary purpose of grooving it is to make room for 85 the sieve.

The spout is designated separately from the side-mouth, because in some uses it may be found best to construct it of material different from that of the container, and in 90 that case, any suitable means for attaching it may be employed.

In order to readily comprehend what follows, it is well to bear in mind; (1) that the neck and side-mouth have no movement, (2) 95 that the stopper and arms have vertical, but no lateral movement, and (3) that the cap has lateral, or rotary, but no vertical movement.

The anchor with the arms attached having been placed in the stopper, the latter is ready for insertion in the ordinary, or top, mouth of the bottle. The arms on the core are placed in alinement with the groove or cut-away of the stopper, and both are inserted in line with the side-mouth, and the alinement is preserved in use by the limiting confinement of the arms in the vertical slots. 100 105

The cap is slotted vertically from near to and just below the outer margin of its top through both sides to form passageways for the arms on the stopper, and, incidentally, such slotting gives effect to resiliency in both sections of the cap, facilitating its emplacement over the shell and shoulder of the bottle neck. The gap, N, has the same purpose of allowing emplacement. After 10 emplacement this gap may be closed in any suitable way, though it is not thought essential to effectiveness that it be closed at all. The emplacement having been made and the stopper pressed down to form a closure, the 15 arm on the same side as the side-mouth extends through the cap at the junction of the vertical and horizontal slots above the top of the shell of the neck, on the extension of the core, and across the top of the stopper. The shield which may be suitably attached to the cap as shown, carries a small sponge or some other suitable material, as a protector of the side-mouth from pollution. They are shown in engagement in the 20 drawing. The device is here shown (in Fig. 1), all ready for pressing the stopper down into the bottle neck, the pressure being applied on the knobs of said arms. This movement having occurred, the cap is shifted around the shoulder on the neck to the left to bring the right hand terminal of the horizontal slot to the arm at U, as shown in Fig. 1, and the other arm has moved in the horizontal slot to the terminal V. That 25 locks the stopper in place and brings the shield over and the protector into the side-mouth. We now have the final emplacement of all the parts which is not disturbed until the container is to be opened and part or 30 all of the contents poured out through the side-mouth and through the sieve and spout, if these adjuncts be usable in the particular instance. When that time has arrived, the cap is again shifted to bring the arms under 35 the entrances to the vertical passageways and the stopper is drawn upwardly to the position shown in Fig. 1. When the quantity required has been emptied the prior positions and relations may be restored. 40 45 50 The cap has the lower portions already mentioned and the apex G above the rim of the mouth. The diameter of this portion is precisely that of the interior of the mouth and neck, and approximately that of the stopper, and the length of the vertical slots measures the extent of upward movement of the arms and stopper to bring the groove or cut-away of the stopper adjacently to the side-mouth. To effect this movement, upward 55 pressure is applied to the knobs, W, of the arms. When the arms have come into contact with the shell of the cap at the tops of the vertical slots at X, the stopper 60 is mainly within the apex of the cap, and

only the diminished lower end is within the 65 neck of the bottle.

As is well known, the shoulders around bottle necks at or near their mouths vary considerably, both as to forms and positions. The illustrations herein are for a rounded shoulder a short space below the top rim; but that this cap and the coacting members can be easily adapted to any of the various forms will be understood without additional explanation or illustrations. 70 75

Having fully described the invention, I claim:

1. A closure, as described, comprising a cap member slotted both vertically and transversely, having rotary movement on the 80 rim of the mouth and on and about a shoulder formed below the mouth on the neck of a bottle member, a stopper carrying horizontally disposed arms adapted to be locked in the transverse slots in the cap, in connection with said rotary movement and to arrest upward movement of the stopper at the upper interior terminals of the vertical slots, in connection with vertical movement of the stopper to unseal the bottle. 90

2. A closure, as described, comprising a cap member slotted both vertically and transversely, having rotary movement on the rim of the mouth and on and about a shoulder formed below the mouth on the neck of a bottle member, a stopper carrying horizontally disposed arms adapted to be locked in the transverse slots in the cap, in connection with said rotary movement and to arrest upward movement of the stopper at the 95 upper interior terminals of the vertical slots, in connection with vertical movement of the stopper to unseal the bottle, said stopper carrying a pull member, said pull member being permanently attached in a recess 100 formed therein and having engagement at its upper terminal with horizontally disposed arms, each arm having a flat outer end for facilitating manipulation. 105

3. A closure, as described, comprising a cap member slotted both vertically and transversely, having rotary movement on the rim of the mouth and on and about a shoulder formed below the mouth on the neck of a bottle member, a stopper carrying horizontally disposed arms adapted to be locked in the transverse slots in the cap, in connection with said rotary movement and to arrest upward movement of the stopper at the upper interior terminals of the vertical slots, 115 in connection with vertical movement of the stopper to unseal the bottle, said stopper being suitably grooved at its lower end to make room for a sieve to be attached therewith, and a sieve adapted for use as a strainer 120 for liquids and a sifter of other substances attached and carried in the groove. 125

4. A closure, as described, comprising a

cap member slotted both vertically and transversely, having rotary movement on the rim of the mouth and on and about a shoulder formed below the mouth on the neck of a 5 bottle member, a stopper carrying horizontally disposed arms adapted to be locked in the transverse slots in the cap, in connection with said rotary movement and to arrest upward movement of the stopper at the 10 upper interior terminals of the vertical slots, in connection with vertical movement of the stopper to unseal the bottle, said bottle member being formed with a gap in its rim to allow the ingress into and egress from the 15 bottle of liquids and other substances, the bottle carrying a spout suitably attached thereto in the gap, the spout adapted to facilitate the pouring out of the contents of the bottle.

20 5. A closure, as described, comprising a cap member slotted both vertically and transversely, having rotary movement on the rim of the mouth and on and about a shoulder formed below the mouth on the neck of a 25 bottle member, a stopper carrying horizontally disposed arms adapted to be locked in the transverse slots in the cap, in connection with said rotary movement and to arrest upward movement of the stopper at the 30 upper interior terminals of the vertical slots, in connection with vertical movement of the stopper to unseal the bottle, said cap member carrying a shield shiftable, in use, out of alignment with a spout suitably attached to 35 the bottle member in a gap formed in its top rim, in the rotary movement of the cap, said shield adapted, while in alignment with the gap and spout, to protect the spout and the exposed portion of the bottle at the gap from 40 breakage; also adapted to carry a protector for the spout.

6. A closure, as described, comprising a cap member slotted both vertically and transversely, having rotary movement on the rim 45 of the mouth and on and about a shoulder formed below the mouth on the neck of a bottle member, a stopper carrying horizontally disposed arms adapted to be locked in the transverse slots in the cap, in connection with said rotary movement and to arrest 50 upward movement of the stopper at the upper interior terminals of the vertical slots, in connection with vertical movement of the stopper to unseal the bottle, said cap member carrying a shield shiftable, in use, out of alignment with a spout suitably attached to 55 the bottle member in a gap formed in its top rim in the rotary movement of the cap, said shield adapted, while in alignment with the gap and spout, to protect the spout and the exposed portion of the bottle at the gap from 60 breakage, also adapted to carry a protector for the spout, and a spout protector formed of sponge cloth or other suit-

able material, attached to and carried by the 65 shield, for preserving the cleanliness of the spout.

7. A closure, as described, comprising a cap member slotted both vertically and transversely, having rotary movement on the rim 70 of the mouth and on and about a shoulder formed below the mouth on the neck of a bottle member, a stopper carrying horizontally disposed arms adapted to be locked in the transverse slots in the cap, in connection with said rotary movement and to arrest upward movement of the stopper at the 75 upper interior terminals of the vertical slots, in connection with vertical movement of the stopper to unseal the bottle, said vertical 80 slots in the cap member extending its full length on two opposite sides from a point near its top, the cap being thereby divided into two sections, each section constituting a gripping portion having a curve to engage 85 and have rotary movement on the shoulder on the neck of the bottle and an interior shoulder adapted to rest and having rotary movement on the rim of the mouth of the bottle.

8. A closure, as described, comprising a cap member slotted both vertically and transversely, having rotary movement on the rim of the mouth and on and about a shoulder formed below the mouth on the neck of a 95 bottle member, a stopper carrying horizontally disposed arms adapted to be locked in the transverse slots in the cap, in connection with said rotary movement and to arrest upward movement of the stopper at the 100 upper interior terminals of the vertical slots, in connection with vertical movement of the stopper to unseal the bottle, said vertical slots in the cap member extending its full length on two opposite sides from a point 105 near its top, the cap being thereby divided into two sections each section constituting a gripping portion having a curve to engage and have rotary movement on the shoulder on the neck of the bottle and an interior 110 shoulder adapted to rest and having rotary movement on the rim of the mouth of the bottle; said vertical slots adapted in connection and coaxing with the arms on the pull member to arrest and limit vertical movement of the stopper, and to guide and preserve in alignment the spout in the gap in the rim of the bottle mouth and the sieve carried by the stopper.

9. A shiftable closure comprising a cap 120 member and a stopper, the stopper shiftable vertically and simultaneously in the neck of a bottle member and in the cap member, the cap member divided by a slot full length from a point near the top on two opposite 125 sides downwardly, each section formed by such division having resilient gripping curves adapted suitably to engage a shoulder

on the bottle neck, said curves having rotary movement on the shoulder, having also interior shoulders having rotary movement on the rim of the mouth of the bottle, and locking means resulting from said rotary movement in connection and coaction with horizontal arms carried by the stopper.

In testimony whereof I affix my signature in the presence of two witnesses.

THOMAS C. SPELLING.
